UNITED STATES PATENT OFFICE.

GEORGE J. THUST, OF MILWAUKEE, WISCONSIN.

WRAPPING MECHANISM FOR PASTEBOARD BOXES.

Application filed August 7, 1922. Serial No. 580,217.

To all whom it may concern:

Be it known that I, GEORGE J. THUST, a citizen of the United States, and resident of Milwaukee, in the county of Milwaukee and State of Wisconsin, have invented certain new and useful Improvements in Wrapping Mechanism for Pasteboard Boxes; and I do hereby declare that the following is a full, clear, and exact description thereof.

10 My invention relates to a new and improved cover wrapping mechanism of the kind which is used in applying the wrappers to paste-board boxes.

Machines which have hitherto been constructed for this purpose are very expensive and since they quickly wear out the enormous expense required to maintain a factory adds materially to the overhead expenses in manufacturing boxes of this kind.

20 The general object of my invention is to provide a machine for doing this work which will be of comparatively simple construction and inexpensive and at the same time one which will operate efficiently.

25 My invention further resides in certain details of construction which are embodied in the machine illustrated in the accompanying drawing, in which:—

Figure 1 is a vertical transverse section 30 of the machine.

Figure 2 is a vertical longitudinal section thereof.

Figure 3 is a sectional plan view.

Figures 4, 5, and 6, are sectional detail 35 views showing the successive stages in the wrapping process, and

Figure 7 is a perspective view showing another detail of the wrapping operation.

Referring specifically to the drawings, 40 the numeral 1 indicates the frame work on which is mounted a table 2 provided with the channelways 3 which intersect at right angles in the center of the table. A supporting block 4 is mounted at the intersection 45 of the channelways. Along this support may be mounted by any suitable means any one of a number of work supporting members 5. These work supporting members are made in different sizes to be used 50 for working on different sized boxes. The portion of the paste-board box 6 to which the wrapper is to be applied is placed on the support 5 together with the wrapper 7 which has been previously coated with glue.

55 The presser-foot 8 is then lowered by means hereinafter described to engage the box and

hold it firmly in position while the wrapper is being applied thereto. The supporting member 5 is provided at its sides and ends with side pieces or plates 9 which are hinged 60 so as to be moved upwardly against the sides of the box, the shoulders 10 being provided to stop this movement when the side pieces reach a perpendicular position. The side pieces 9 are provided with clips 11 at the ends 65 which are provided for the purpose of folding the edges over the ends of the boxes as shown in Figure 7. The side plates 9 are hinged to the support 5 and strips 14, hereinafter described, are hinged to the plates, 70 and these members together constitute a single unit. These units are made in various sizes to accommodate different size boxes and are adapted to be interchanged. The rollers 12, it will be noted, have neither direct nor permanent connection with either the plates 9 or the strips 14, but are adapted to operate them in sequence, that is, the rollers engage the plates 9 first, and thereafter, upon continued motion, operate the strips 14. 75 Obviously, therefore, the rollers 12, through their operating and supporting means, hereinafter described, may be adjusted to accommodate units of different sizes.

Starting with the box and wrapper in position shown in Figure 4 the rollers 12 which are carried by the arms 13 are raised vertically by means hereinafter described thus folding the wrapper against the outer sides of the box as shown in Figure 5 and folding the end over the ends of the box as shown in Figure 7. The hinged portion 9 also carries a hinged strip 14 which is provided with a rearwardly extending spring-finger 15. Upon further movement of the roller 12 80 this strip 14 is turned over into the position shown in Figure 6. At this point the spring-finger 15 is under considerable tension and the wrapper is firmly pressed against the sides of the box.

For the purpose of moving the rollers upwardly the arms 13 which carry the rollers are secured to a vertical rack 16 which is mounted in a vertical guideway carried by an adjustable plate 17 which is mounted in one of the channelways 3 and secured for adjustment by any suitable means for adjusting it to different sized boxes. The rack 16 is raised by means of a segment 18 connected therewith, said segment being keyed to the shaft 19 which may be operated by the hand-crank 20. The plate 17 is provided with a

22

downwardly extended bearing 21 provided with a yoke 22 which holds the segment and rack operatively connected in all positions of adjustment.

5 After the rollers have been raised to apply the wrapper to the sides of the box the oppositely disposed rollers are raised to apply the end portions of the wrapper. This latter operation is accomplished by the side 10 pieces 9^a and strips 14^a which are similar in all respects to the side pieces 9 and strips 14 except that they have no clip 11 attached thereto.

In order to limit the movement of the rollers 12 to the position shown in Figure 6 so that they will not ride off over the ends of the spring-fingers 15 I have provided each of the rack bars 16 with a stop 23. This stop is adjustably mounted so as to provide for 20 boxes of different height.

In order to provide suitable means for raising and lowering the presser-foot 8 it is secured to the lower end of an arm 24 which is carried by a yoke 25 slidably mounted on 25 the vertical standard 26. This yoke is provided with a stud 27 which is connected by means of a link 28 to an arm 29 extending over the rock shaft 30. A treadle 31 is mounted on the rock shaft for the purpose 30 of rocking the same.

After the wrapper is secured to the box and the rollers 12 again lowered the operator presses on the treadle 31 to raise the presser-foot. The presser-foot is provided 35 with holes which register with the vertical rods 32 secured to the upper end of the standard 26. When the presser-foot is raised the rods 32 project downwardly through the holes therein and positively remove the box therefrom, whereupon the box 40 may be dropped into a suitable receptacle and the machine is ready for the next operation.

From the above description it will be seen 45 that I have constructed a simple and inexpensive machine and yet one which may be operated as rapidly as the much more expensive machines now in use. I have described in detail one form in which my invention 50 may be embodied but it will be understood that the invention is not limited to the precise structure herein shown and described but that many modifications may be made therein without departing from the 55 spirit of the invention.

I claim:

1. A machine for wrapping multisided boxes, comprising a support for the wrapper and the box, a plate for each side of said 60 box hinged to said support, a strip for each plate and hingedly joined thereto, and a single movable member for each plate and its corresponding strip adapted to successively operate said plate and strip to force 65 the wrapper against the side of the box and

completely fold the wrapper over the edge of said box and against its inner side.

2. In a wrapping mechanism for pasteboard boxes, interchangeable means for operating upon wrappers and boxes of different sizes and holding them in position, said means comprising a support and plates, means hinged to said support for folding the wrapper against the outer side portion of the box, means hinged to said plates for subsequently folding the wrapper against the inside of the side portion, means for operating said plates and hinged means, and means for adjusting said operating means to accommodate different sized boxes. 80

3. In a wrapping mechanism for pasteboard boxes, means for supporting the wrapper and box in position to be operated upon, a vertically movable arm having a roller thereon, means located in the path of the roller and operable thereby to fold the wrapper against the outer side portion of the box, and means operable by further movement of the roller in the same direction to fold the wrapper against the inner side portion of the box. 85

4. In a wrapping mechanism for pasteboard boxes of varying sizes, interchangeable means for supporting wrappers and boxes in position to be operated upon, a vertically movable arm having a roller thereon, means located in the path of the roller and operable thereby to fold the wrapper against the outer side portion of the box, means operable by further movement of the roller in 90 the same direction to fold the wrapper against the inner side portion of the box, and means for adjusting said operating means to accommodate supports for different sized boxes. 95

5. In a wrapping mechanism for pasteboard boxes, means for supporting the box and wrapper, a presser-foot for holding the same while being operated upon, side pieces hinged to the supporting means and movable to fold the wrapper against the outer side portion of the box, means for limiting the movement of the side portion to a position at right angles to the supporting means, means hinged to said side piece for subsequently folding the wrapper against the inside of the side portion, means for operating said hinged portion, and means passing thru said presser foot for positively removing the box from the presser-foot after 110 the wrapping operation is completed. 115

6. In a wrapping mechanism for pasteboard boxes, means for supporting the box and wrapper, a presser-foot for holding the same while being operated upon, a vertically 125 movable arm at each side of the box and having a roller thereon, a side piece hinged to the supporting means and engageable by the roller upon its upward movement to fold the wrapper against the outer side portion 130

of the box, a strip hinged to said side piece and having a spring finger engageable by said arm and roller upon further upward movement thereof to fold the wrapper against the inside of the side portion, and means for positively removing the box from presser-foot after the wrapping operation is completed.

7. In a wrapping mechanism for paste-board boxes, means for supporting the box and wrapper in position to be operated upon, an arm guided for vertical reciprocatory movement at each side of the box, a rack and segment for operating each arm and operable upon upward movement of said arms to fold the wrapper against the sides of the box and against the inside faces thereof.

8. In a wrapping mechanism for paste-

board boxes, interchangeable means for supporting wrappers and boxes of different sizes in position to be operated upon, an arm guided for vertical reciprocatory movement at each side of the box, a rack and segment for operating each arm, means operable upon upward movement of said arms to fold the wrapper over the sides of the box and against the inside faces thereof, and means for adjusting said operating means to accommodate the supports for different sized boxes.

In testimony that I claim the foregoing I have hereunto set my hand at Milwaukee, in the county of Milwaukee and State of Wisconsin.

GEORGE J. THUST.
